(57) CLAIM

The ornamental design for a combined dish washing machine and drying machine, as shown and described.

DESCRIPTION

FIG. 1 is a top perspective view of a combined dish washing machine and drying machine of the present invention;

FIG. 2 is a front view thereof;

FIG. 3 is a first side view thereof;

FIG. 4 is a second side view thereof; and,

FIG. 5 is a top view thereof.

The ornamental design which is claimed is shown in solid lines in the drawings. Any broken lines in the drawings are for illustrative purposes only and form no part of the claimed design.
